GRATE STRUCTURE

John W. Hulson, Keokuk, Iowa, assignor to
Hulson Grate Company, Keokuk, Iowa

Application July 30, 1940, Serial No. 348,473

1 Claim. (Cl. 126—180)

The invention relates to a locomotive grate structure of the general type disclosed in my U. S. Patent No. 2,009,450 of July 30, 1935, in which various grate sections were formed of fingers assembled on rocker bars and were provided with tuyères for conducting and baffling the draft air for the fire. With the patented structure, like others employing shaker sections and a shaker rigging therefor, the grate sections were inevitably frequently tilted from normal by the shaker rigging, due to expansion and contraction of rigging and fire box, and this condition was aggravated with wear of trunnions, pivots, etc. Such tilting, causing one end of the fingers of any grate section to rise and the other end of the fingers of the next grate section to lower, created straight-draft openings through which some of the draft air could pass through the grate without being subjected to the baffling action of the tuyères. While these straight-draft openings were not objectionable in the era in which the aforesaid patent issued, they later caused a great deal of trouble and fuel loss when locomotive speeds and loads were increased and fine fuels, often screenings of very light sub-bituminous coal, were used. Under these conditions, quite an amount of fuel was lost to the ash pit through the aforesaid straight-draft openings when "standing by," and similar loss often occurred when running with light draft. Moreover, when operating at high speeds and under heavy loads requiring forcible draft, the unbaffled draft air passing through said straight-draft openings, would carry burning fuel from the grate through the locomotive flues and stack, not only wasting fuel but causing slagging of flues, and cinder cutting. The present invention aims to so improve the grate finger of the aforesaid patent as to overcome the above discussed difficulties, and extended use of locomotive grates having the improved fingers, has proven that the desired end has been attained.

With the foregoing in view, the invention resides in the novel subject matter hereinafter described and claimed, description being accomplished by reference to the accompanying drawings.

Figure 1 is a fragmentary top plan view showing a grate constructed in accordance with the present invention.

Figure 2 is a vertical longitudinal sectional view on line 2—2 of Fig. 1 showing the grate sections in cold grate position.

Figure 3 is a diagram showing portions of two adjacent grate sections in cold grate position.

A preferred construction has been illustrated and will be rather specifically described, with the understanding, however, that within the scope of the invention as claimed, variations may be made. While the description will relate to a structure in which each grate section includes separate fingers on a finger bar, it is to be understood that the improvements are equally applicable to a unitary grate section.

10 Each grate section in the present disclosure comprises a finger bar 10 and a plurality of fingers 11 mounted thereon, the pivots of the finger bars being denoted at 12. These finger bars are provided with the usual downwardly projecting arms 13 which are pivoted to the conventional shaker rigging 14.

Each finger 11 comprises an enlarged head 15 extending longitudinally of the upper edge of a vertical web 16, and said head consists of a longitudinal ridge 17 and ribs 18 extending longitudinally of the lower portion of said ridge. The ridge 17 is centrally located and there are two of the ribs 18 projecting laterally from the opposite sides of said ridge. When a plurality 25 of the fingers 11 are assembled in side-to-side contact upon a finger bar 10 to form a complete grate section, the ribs 18 form the bottoms of air-conducting valleys 19 between the fire-supporting ridges 17. The valleys 19 have suitable air inlet openings or tuyères 20 which baffle and diffuse the draught air drawn through the grate under the influence of the locomotive exhaust, and the fire-supporting ridges 17 are formed with transverse air-conducting channels 21. Every-30 thing so far described is disclosed in the above mentioned patent. My improvement, however, resides in novel structure including end walls 22 for the valleys 19, said end walls being joined to the ridges 17 and to the lateral ribs 18. Each 35 end surface of each finger head 15 consists of an upper half 17^a disposed substantially in a transverse plane inclined in one direction, and a lower half 17^b disposed substantially in a second transverse plane inclined in the other direction, said 40 upper and lower halves converging to a transverse horizontal ridge line 23 at the extreme end of said head 15. The end walls 22 at opposite sides of the ridge 17 extend upwardly from the ribs 18 to the ridge line 23 and the outer trans-45 verse sides of these walls form portions of the inclined lower half 17^b of the above described end surface of said head 15.

When the grate sections are in cold grate position or otherwise in slightly tilted position 50 as seen in Figs. 2 and 3, a certain distance 25

(Fig. 3) exists between the end wall tips 23 at one end of the valleys 18 of any grate section, and the adjacent wall heels 24 of the next grate section. This space, due to the provision of the inclined walls 22, is considerably less than the shortest distance which would exist between the adjacent ends of the valley bottoms 18, were said walls 22 not employed. Thus, with the improved end structures including these walls, there will be less loss of fuel between grate sections when these sections occupy cold grate position, and as the fire is started and a bed of coals forms on the grate, the expansion of the fire box and the shaker rigging 14 will bring the various grate sections to substantially horizontal position for operation. Also, during operation, should the grate sections again become slightly tilted, no straight-draft openings of objectionable size will be formed between them and, therefore, the previous difficulty with respect to stack loss, cinder cutting and flue slagging, will be overcome. The walls 22 do not materially interfere with shaking the ash through the grate nor with dumping the fire and they provide an increased vertical section at the ends of the fingers which will increase the life of the latter in addition to giving the above described advantages.

In Fig. 3, in order to emphasize the extent to which the distance 25 is decreased over the distance which would exist if the walls 22 were not used, I have placed dotted lines 27 on the view, even with the upper sides of the ribs 18. By considering the walls 22 cut off along the dotted lines 27 and comparing the distance 26 which would then exist between the fingers of adjacent grate sections with the latter tilted, with the distance 25 which would exist when using the walls 22, it may be readily seen that a marked reduc-

tion in the space between adjacent grate sections, when in cold grate or other slightly tilted position, has been effected, to prevent fuel from sifting into the ash pit and to prevent stack loss, cinder cutting and flue-sludging.

While it is to be understood that I am not restricted to exact proportions or dimensions, I have found that excellent results exist when each wall 22 extends above the rib 18 a distance substantially equal to the vertical thickness of said rib and when the inclined surface 17^b is at substantially 120° to the lower side of the rib 18.

What is claimed is:

A tuyère-type grate finger comprising a vertical web having an elongated head extending along its upper edge, said head having a central longitudinal fire-supporting ridge and lateral ribs extending longitudinally throughout the length of the lower portion of said ridge, said ridge having draft-air-baffling tuyères, each end surface of said head consisting of an upper half disposed substantially in a transverse plane inclined in one direction and a lower half disposed substantially in a second transverse plane inclined in the other direction, said upper and lower halves converging to a transverse horizontal ridge line at the extreme end of said head, said ridge line being in a plane above the upper sides of said ribs, and transverse end walls integrally joined to said ribs and to the lower portions of the lateral sides of said fire-supporting ridge, said end walls extending upwardly from said ribs to said transverse horizontal ridge lines at the extreme ends of said head and having outer sides forming portions of said inclined lower halves of said end surfaces of said head.

JOHN W. HULSON.
